JOHN R. HAYNES, OF NEWPORT, KENTUCKY, AND AMOS F. WORTHINGTON, OF CINCINNATI, OHIO, ASSIGNEES TO SMITH AND WORTHINGTON, OF CINCINNATI, OHIO.

Letters Patent No. 68,073, dated August 27, 1867.

IMPROVED MEDICINE-CASE.

The Schedule referred to in these Letters Patent and making part of the same.

TO WHOM IT MAY CONCERN:

Be it known that we, JOHN R. HAYNES, of Newport, in the county of Campbell, State of Kentucky, and AMOS F. WORTHINGTON, of Cincinnati, in the county of Hamilton, and State of Ohio, have invented a new and useful Improvement in Medicine-Cases.

Our invention relates to an arrangement where two or more series of vials in a medicine-case or chest are made readily accessible, and maintained at all times with their mouths upward, whether the case be open or shut.

Figure 1 is a perspective view of a case embodying our invention, the same being shown with open cover, and having one slide elevated and folded over, so as to expose the lower tier.

Figure 2 is a transverse section of the same in the closed condition.

Figure 3 shows one of our slides detached.

A is the body of the case proper, having a side-flap, B, and a cover, C, which flap and cover have a hinge or flexible connection, b c, with the said body at its lower front corner and upper rear corner respectively, and the said cover having a flap, C'. The ends of the case have inside vertical grooves A' A' for slides D D' D'' D''' D''', each of which has a horizontal joint or flexible portion, d, at its mid-height, so as to constitute a pair of leaves, d' d'', each of which has a vial-rack, which may consist of a series of loops, E, of leather or other suitable material. The lower edge of each leaf has a horizontally projecting ledge or shelf, F F', which serves to support the tier of vials, and of which the upper ledge F' also serves, when the case is closed, to hold in the corks of the lower tier of vials, those of the upper tier being similarly held by the cover C. A tag, G, projecting from the top of each slide, enables either one of them to be lifted and folded over, as seen in fig. 1, or to be removed entirely from the case. For a larger class of vials, one or more of the slides may be inflexible. (See D''', fig. 2.) The flap and cover may be held to the closed position by means of any suitable catch, H, and when so closed a handle, I, upon the cover, enables the case to be easily carried about. A pocket, J, for prescriptions, powder-papers, &c., may be provided in the rear part of the case.

Several very decided advantages accrue from the above arrangement. For example, ready and convenient access is afforded to every vial in the case, and no vial is at any time in an inverted position, and therefore no liable to leak or the cork becoming loose. Every vial and every cork is securely held to its proper place. This improvement may be applied to any desired form of medicine-case or chest.

We claim herein as new and of our invention—

1. The provision in a medicine-case of one or more sliding and folding vial-racks, substantially as set forth
2. The provision upon such racks of the ledges F F', for the purpose set forth.

In testimony of which invention we hereunto set our hands.

J. R. HAYNES,
A. F. WORTHINGTON.
